UNITED STATES PATENT OFFICE.

JOSEPH EIFEL, OF DETROIT, MICHIGAN.

WRENCH.

Application filed October 29, 1917. Serial No. 199,034.

To all whom it may concern:

Be it known that I, JOSEPH EIFEL, a citizen of the United States, and a resident of Detroit, in the county of Wayne and

5 State of Michigan, have invented certain new and useful Improvements in Wrenches, of which the following is a specification.

My present invention relates to wrenches, more particularly those of the type in which 10 the shank of one jaw slides relatively to the shank of the other jaw longitudinally of the wrench as a whole.

The principal objects of my present invention are the provision of improved means 15 for moving the jaws of a wrench relatively to each other, the provision of improved means for adjusting the position of the jaws of a wrench relatively to each other; the provision of improved means for operating wrenches of the type in which the shank 20 of one jaw slides relatively to the shank of the other jaw longitudinally of the device as a whole; the provision of improved means for adjusting the relative position of 25 the two shanks of a wrench of this type; the provision of improved means for adjusting the position of the operating lever relatively to the parts moved thereby; the provision of improved means for preventing 30 accidental disengagement of the movable jaw from the other parts of the wrench; the provision of yielding means for preventing accidental disengagement of the movable jaw from the other parts of 35 the wrench while allowing disengagements when desired; the provision of an improved ratchet connection between the movable jaw and its operating lever; the provision of means for enabling a wrench to be used as 40 a vise; the provision of means for moving the jaws towards each other a short distance with greater leverage than that obtainable by the manual means normally employed alone for moving the jaws towards and 45 away from each other a greater distance; the provision of means for clamping the jaws in any desired position; and generally to improve, simplify and cheapen the construction of wrenches.

50 In attaining these and other objects and advantages to be hereinafter set forth, I have provided a construction, various embodiments of which are illustrated in the accompanying drawings, in which:—

55 Figure 1 is a side view of a wrench constructed in accordance with my invention;

Fig. 2 is a transverse section on the line 2—2 of Fig. 1;

Fig. 3 is a transverse section on the line 3—3 of Fig. 1;

Fig. 4 is a side view of a modified form of jaw;

Fig. 5 is a side view of a further form of jaw;

Fig. 6 is a side view of a still further form of jaw; and

Fig. 7 is a view of the jaws shown in Fig. 6 taken on the line 7—7 of Fig. 6; and Fig. 8 is an alternative form of construction of a part of the wrench shown in Fig. 1.

Referring to the form of construction shown in Figs. 1 to 3, 1 and 2 represent the two jaws of the wrench attached respectively to the shanks 3 and 4. The shank 3 is arranged to slide longitudinally within a slot or aperture of substantially rectangular cross section in the shank 4, which acts as one of the operating levers of the wrench. The shank 3 is moved relatively to the shank 4 by means of the toothed segment 5 adapted to engage teeth 6 of the rack formed on the shank 3. This segment 5 is connected to the lever 7 by means of the pin 8 to secure the segmental part 5 and the lever 7 to the pin 8, so that by moving the lever 7 towards and away from the shank or lever 4, the jaws 1 and 2 are caused to approach or recede. The segment 5 is made sufficiently narrow so that by moving the lever 7 away from the lever 4, sufficiently far, the teeth of the segment 5 may be moved away from the teeth 6 of the shank 3 to allow the relative position of the lever 7 and the shank 3 with its jaw 1 to be varied as desired.

The lever 7 and the segment 5 are carried by two lugs 9 and 10, depending from the lever 4, by means of the pin 8. The pin 8 is connected to the segment 5 by means of a screw 11 and to the side end portions 7^a of the lever 7 by squared portions 8^a and 8^b. Between these squared portions is a cylindrical portion 8^c which enables the lever and segment to pivot easily in the lugs 9 and 10. The squared portions 8^a and 8^b are respectively larger and smaller than the central cylindrical portion 8^c, so that the pin can be inserted through the various parts from one side and retained in position by a screw 12 inserted in a threaded aperture at the smaller end of the pin 8.

Instead of providing circular holes in the

2

lugs 9 and 10, I prefer to employ diagonal slots 13 sloping rearwardly away from the jaws. Pressure on the levers to bring the jaws together holds the pin 8 against the uppermost end of the slot (viewed from the position shown in Figure 1 of the drawings) while pressure on the end of the jaw 1 directed inwardly will tend to push the segment 5 rearwardly with the result that the pin 8 will be moved diagonally along the slots 13 sufficiently to allow the teeth of the segment 5 to clear the teeth of the shank 3 and enable the latter to move rearwardly to the desired extent. Any force tending to separate the jaws will only press the pin 8 more firmly against the uppermost ends of the slots 13, so that the latter provide for a ratchet action between the shank 3 and the segment 5 in one direction, that is, in causing the jaws to approach.

In order to hold the parts in position, under normal conditions, I have provided a spring 21 riveted at 22 to the lever 4 and bearing at its other end against the under surface of the segment 5. The lugs 9 and 10 are arranged to extend below the lower surface of the segment 5, so that the end of the spring 21 normally lies between them and is thereby prevented from moving laterally.

In order to prevent the shank 3 becoming accidentally disengaged from the other parts of the wrench when the segment 5 has been moved out of engagement with the teeth 6 of the shank without preventing disengagement when desired, I have provided a spring catch 14. In the form of construction shown this catch 14 is attached to the end of the shank 3 so as to leave its upper rounded end 14^a projecting laterally sufficiently far to engage the part 4^a of the lever 4 without projecting too far to prevent the spring bending under pressure to bring the part 14^a under the part 4^a. The part 4^a is so located that the spring catch 14^a will not contact therewith within the range of jaw opening for which the wrench is designed.

A releasable lock is provided which serves several purposes first to hold the levers 4 and 7 in adjusted position, and second to bring these levers together with greater force than is obtainable by manual pressure alone on the levers 4 and 7, and third to adjust the locked position of the levers 4 and 7 and thereby firmly hold the jaws 1 and 2 within small limits. This lock comprises a ratchet-toothed lever 17 pivotally mounted at 24 on the end of a lever 18. This lever 18 is pivotally mounted at 25 on the lever 4. The end 18^a of this lever is arranged to be engaged by an inclined face on a slide member 19 adapted to move to and fro in a slot 20 in the handle 4.

When the levers 4 and 7 are separated, the

spring 26 acting on the end of the toothed lever 17 holds it in proper position for engaging the toothed member 16 at such time as the levers 4 and 7 are brought together in gripping an object. If the member 19 is moved towards the ratchet-toothed lever 17 the latter by means of lever 18 is drawn towards the lever 4 and consequently by reason of the engagement of the teeth on the members 16 and 17 brings the levers 4 and 7 together. In order to hold the members 16 and 17 in engagement the spring 26 is mounted on the lever 18 adapted to bear against the end of the lever 17 which is inclined so that the spring contacts as shown with its rear edge only. In order to bring the lever 17 into inoperative position it is moved through 90° into the position shown in dotted lines in Fig. 1 by insertion of the fingers between the handles 4 and 7 in which position it is releasably held by the spring 26.

In Fig. 8 is shown a device which may be used in place of the slide member 19 for moving the lever 18. This device comprises a knurled nut 27 journaled in an aperture in the lever 4, through which nut passes a threaded pin 28 loosely pivotally connected at 29 to the end 18^a of the lever 18.

By means of the construction just described, the wrench may be employed as a vise, large adjustments being made by varying the position of the segment 5 relatively to the shank 3, smaller adjustments by varying the engagement of the teeth on the members 16 and 17 and the final holding on adjustment by means of the lever 18. The adjustment of the lever 18 having very considerable leverage can be employed to produce a more continuous force on the jaws 1 and 2 than is ordinarily applicable by means of manual pressure on the levers 4 and 7.

In Figures 4 to 7 modified forms of jaws are shown, which may be used in place of those illustrated in Figure 1. In the form of construction shown in Figures 6 and 7, a transverse notch 30 is provided in the opposing jaw faces as well as a longitudinal notch 31. This construction makes it possible to grip a nut on the opposite corners with the wrench in two positions, i. e. with the jaws perpendicular to the base of the nut and with the jaws parallel to the axis of the nut. The last mentioned position is frequently required when there is little or no room to operate the wrench in the first mentioned position.

Having thus described my invention and illustrated its use, what I claim as new and desire to secure by Letters Patent is:—

1. A device of the kind described, comprising, in combination, a pair of jaws, a pair of shanks connected to said jaws and adapted for relative sliding movement,

- means for moving said shanks relatively to each other, yieldingly resistant means tending to prevent accidental disengagement of said shanks in their predetermined position, 5 but constructed and arranged to permit voluntary disengagement or movement of said shank for varying the relation between the said jaws upon the application manually of a predetermined separating pressure upon 10 the shanks.
2. A device of the kind described, comprising, in combination, a pair of jaws, a pair of shanks connected to said jaws and adapted for relative sliding movement in each instance, one of said shanks being extended to form an operating rigid lever, and an auxiliary lever having a ratchet connection with one of said shanks and adapted to move it relatively to the other lever, whereby 15 said jaws may be brought towards each other without separating said levers, said auxiliary lever having its operating handle portion on one side of said extended shank and its ratchet connection on the other. 20
3. A device of the kind described, comprising, in combination, a pair of jaws, a pair of simple, operating levers for directly giving the jaws relative movement, and supplemental means for increasing the tension 25 between said operating levers.
4. A device of the kind described, comprising, in combination, a pair of jaws, a pair of operating levers therefor, a ratchet-toothed member on each of said levers 30 adapted to engage each other, and means for moving one of said members toward its lever without disengagement from the other member and thereby increasing the tension between said operating levers, said means holding the levers independently of the operator's pressure locked in predetermined position. 35
5. A device of the kind described, comprising, in combination, a pair of jaws, a pair of operating levers therefor, a member on each of said levers adapted to engage detachably the opposite member and means for moving one of said members towards its lever without disengagement from the other member and thereby increasing the tension 40 between said operating levers, said means holding the levers independently of the operator's pressure locked in predetermined position. 45
6. A device of the character described, comprising, in combination, a shank having a jaw, an extended portion serving as a lever, and a pivot support, a second shank having a jaw and a rack facing said pivot support, said two shanks being slidable relatively to each other and longitudinally of the device, and a toothed member and an operating handle therefor pivotally mounted in said support, said toothed member being 50 adapted for engaging said rack, and said handle being adapted to cause said jaws to approach when the handle is moved towards the extended portion of the first mentioned shank, and said toothed member and handle being adapted to permit variation of the engagement of the toothed member with the rack by means of lineal and rotatory movement of the handle, and said jaws and said pivot support being disposed on one side of the longitudinal axis of the device and said operating handle being disposed on the other side thereof. 55
7. A device of the character described, comprising, in combination, a shank having a jaw, an extended portion serving as a lever, and a pivot support, a second shank having a jaw and a rack facing said pivot support, said two shanks being slidable relatively to each other and longitudinally of the device, and a toothed member and an operating handle therefor pivotally mounted in said support, said toothed member being adapted for engaging said rack, and said handle being adapted to cause said jaws to approach when the handle is moved towards the extended portion of the first mentioned shank, and said handle being also adapted to impart substantial longitudinal movement to said rack through said gear upon outward movement of the lever, and also to move 60 said gear out of engagement with said rack to permit variation of the engagement therebetween, and said jaws and said pivot support being disposed on one side of the longitudinal axis of the device, and said operating handle being disposed on the other side thereof. 65
8. In combination relatively slidable members having complementary gripping jaws, one of said members being extended to form a lever, a second lever pivoted on the said last mentioned member for cooperation with first said lever to relatively slide said members, and means adjustable on said first lever and having connection with the second lever for increasing the leverage imposed upon 70 said relatively slidable members. 75
9. In combination relatively slidable members having complementary gripping jaws, one of said members being extended to form a lever, a second lever pivoted on the said last mentioned member for cooperation with first said lever to relatively slide said members and an auxiliary lever on said first mentioned lever for establishing detachable connection between said first and second levers, for increasing the leverage imposed by the same. 80
10. In combination relatively slidable members having complementary gripping jaws, one of said members being extended to form a lever, a second lever pivoted on the said last-mentioned member for cooperation with the first said lever to relatively slide said members, and means for increasing 85

the leverage imposed upon said relatively slideable members, comprising means operating independently of the hand pressure for locking said levers in position.

11. In combination relatively slideable members having complementary gripping jaws, one of said members being extended to form a lever, a second lever pivoted on the said last mentioned member for co-operation with first said lever to relatively slide said members, an auxiliary lever detachably connecting said first and second levers, and means for actuating said auxiliary lever, for increasing the leverage imposed by said first and second levers.

12. In combination relatively slideable members having complementary gripping jaws, one of said members being extended to form a lever, a second lever pivoted on the said last mentioned member for co-operation with first said lever to relatively slide said members, an auxiliary lever pivoted on one of first said levers and having detachable connection with the other of said levers, and means for actuating said auxiliary lever for moving said first and second levers together.

13. In a wrench, a pair of relatively slideable shanks having complementary jaws, one of said shanks being extended to form an operating lever, means for moving said shanks relatively to vary the distance between said jaws, yieldingly resistant means on one of the shanks for preventing their accidental disengagement, and auxiliary means connecting said lever and first said means for increasing the leverage imposed on said shanks.

14. A device of the kind described, comprising, in combination, a pair of jaws, a pair of shanks connected to said jaws and adapted for relative sliding movement, one of said shanks being extended to form an operating lever, and an auxiliary lever having an operating connection with one of said shanks and adapted to move it relatively to the other lever, whereby said jaws may be brought towards each other without separating said levers, said auxiliary lever having its operating handle portion on one side of said extended shank and its operating connection on the other.

In testimony whereof, I have hereunto signed my name.

JOSEPH EIFEL.
